UNITED STATES PATENT OFFICE.

ALEXANDER B. ROE, OF ATHENS, OHIO.

BOOK-DRILLING MACHINE.

Application filed March 27, 1925. Serial No. 18,797.

This invention relates to book-binding machines, and has particular reference to such a machine having means for forming, and applying, a metal back to a particular 5 volume under construction.

The present invention contemplates a machine of the above mentioned character having means for receiving a volume of matter to be bound, retaining such matter 10 in position, measuring and shaping a metallic back in accordance with the size of the volume, and retaining such metallic back upon the volume during the drilling and binding process.

15 The invention further contemplates the use of safety means, whereby the operation of the drilling mechanism will be prevented during the adjustment of the drills, and further, to prevent the adjustment of such 20 drills while the machine is in operation.

Other important objects and advantages of the invention will be readily apparent during the course of the following description.

In the accompanying drawings:

25 Fig. 1 is a perspective view of a machine embodying the invention;

Fig. 2 is an end elevation thereof;

Fig. 3 is a plan view thereof;

Fig. 4 is a front elevation view;

30 Fig. 5 is a central vertical longitudinal sectional view thereof;

Fig. 6 is a horizontal sectional view, taken on line 6—6 of Fig. 2;

Fig. 7 is a vertical sectional view through 35 a pressure bar and associated elements;

Fig. 8 is a similar view, but with the parts in slightly different position, preparatory to drilling;

Fig. 9 is an enlarged vertical sectional 40 view through a measuring and shaping mechanism for the metallic backs;

Fig. 10 is a similar view showing the first gaging and bending operation;

Fig. 11 is a similar view illustrating the 45 final shaping of the metal back;

Fig. 12 is an end elevation of a metal back shaped for application to the volume;

Fig. 13 is a perspective view of a completed volume;

50 Fig. 14 is an elevation of a pair of interlocking binding nails employed in the binding;

Fig. 15 is a sectional view through an adjustable drill mounting.

Fig. 16 is a side elevation of a safety latch 55 in one locking position; and

Fig. 17 is a similar view with the parts moved to a second locking position.

Referring specifically to the drawings, the numeral 10 designates a rectangular base 60 frame member. This base member carries vertical, parallel, supporting, and guide rods 11, 12, 13 and 14, rigidly secured thereto. The rods 11 and 12 at their upper ends are 65 connected by a horizontal cross bar 15, and the bars 13 and 14 are connected at their upper ends by a horizontal cross bar 16, both the bars 15 and 16 being rigidly attached to these rods. A transverse horizontal bar 17 is bolted, or otherwise attached, to the bars 70 15 and 16 adjacent their forward ends. This bar 17 forms a part of a measuring and shaping mechanism, to be hereinafter described. The rods 11 and 12, and 13 and 14, 75 carry bars 18 and 19 rigidly secured thereto, and in parallel relation to the bars 15 and 16. Rigidly attached to the bars 15 and 18 80 is a vertically arranged supporting bar 20, and a similar bar 21 is attached to the bars 16 and 19, both bars 20 and 21 lying parallel to the rods 12 and 14.

The numeral 22 designates a work table as a whole, upon which the volume to be bound is supported and clamped in position during the drilling operation. This table comprises 85 a top 23, bolted, or otherwise secured, at its forward edge to a transverse bar 24, and at its rear edge to a transverse bar 25. The bars 24 and 25 are carried by longitudinally 90 extending guide rods 26, having a sliding bearing in guide brackets 27. The guide brackets 27, in turn, are slidably mounted upon the guide rods 12 and 14. The supporting bar 24 has bolted, or otherwise secured, to its upper face a plate 28, provided 95 at its forward edge with equidistantly spaced notches, as indicated at 29, and hinged at its rear edge, as at 30, to the bar 24. The bar 24 is arranged between the bars 20 and 21, but has no positive connection therewith. 100 The bars 20 and 21 are provided with notches 31, as clearly indicated in Figs. 16 and 17. These notches are adapted to receive pins 32 extending outwardly from the ends of the bar 24, and in normal position of the bar 24 105 these pins lie wholly within the notches 31, and when in such position movement of the table 22 in a vertical direction is prevented.

The bars 20 and 21 carry lateral extensions 33 adjacent their lower ends and slightly below the notches 31. These extensions 33 are adapted to have pivotally mounted thereto latch members 34, notched as at 35 and provided with an upwardly extending finger 36. As clearly shown in Fig. 17, these latch members 34 are adapted to partake of vertical movement whereby the fingers 36 will pass over the pin 32 to thereby retain such pin in the slot 31, for a purpose to be hereinafter described. The bars 20 and 21 are also provided with depending, pivotally mounted, co-acting, latch members 37 adapted, when in one position, to swing into the path of movement of the finger 36. The purpose of this latch member 37 will be fully set forth hereinafter.

As before stated, the table 22 is adapted to receive thereon the matter to be bound. Means are employed for binding the material in position upon the table, and such means comprise a pressure bar, indicated as a whole by the numeral 38, and a pair of parallel bars 39, carrying at their opposite ends blocks 40. Rigidly attached to the lower edges of the bars 39 is a pressure plate 41, identical in size and shape with the plate 28, and arranged parallel therewith. The plate 41 is provided upon its forward edge with equidistantly spaced notches 42, corresponding to notches 29 and arranged in vertical alignment therewith. This pressure bar is adapted to partake of vertical movement with respect to the plate 28, and the means to carry out this movement comprises a pair of fixed, vertically arranged, screws 43, having their lower ends rigidly attached to the bar 24. The blocks 40 carry worms 44 and worm-wheels 45, the worm-wheels 45 being threaded upon the screws 43 but fixed within the boxes 40, and being free to rotate therein. The worms 44 are in turn mounted upon a transversely extending shaft 46 having bearings within extensions of the blocks 40. The shaft 46 extends outwardly of the frame of the machine and carries at its outer end a hand-wheel 47, having a hand crank 48. It is, therefore, obvious that rotation of the shaft 46 will result in the rotation of the worm wheels 45, to thereby cause the pressure bar 38, and associated elements, to partake of vertical reciprocating movement toward, or away from, the co-acting plate 28. It will therefore be seen that a volume placed upon the table may be securely clamped in position thereon for the purpose of drilling, etc.

The table 22 carries an evener board 49 adjustable thereon through the medium of a slot 50 and a set screw 51. The numeral 52 designates a combined auxiliary work table and evener board. This table 52 is arranged adjacent the front of the machine and lies transversely thereof. The table 52 is piv-

otally supported, as at 53, to brackets 54, carried by the bars 18 and 19, and is adapted to swing in a vertical plane to a position as indicated in dotted lines in Figs. 5 and 7, which position brings the plate in direct contact with the forward edges of the plates 28 and 41. It will therefore be seen that through this means the volume may be conveniently evened with respect to the forward edges of the plates 28 and 41. When in a horizontal position the table 52 is supported by vertical, parallel, support rods 55, carried by the base frame 10.

The means employed for drilling a volume comprise upper and lower sets of drills indicated as a whole by the numerals 56 and 57. In the present instance I have illustrated four upper drills and four lower drills, although it is to be understood that this number may vary in accordance with the needs arising during the binding of various types of volumes. The drill mechanisms employed are identical, with the exception that the upper set is inverted, and a description of one will suffice for all. The drill mechanism embodies a housing 58 provided with a vertical opening 59 for receiving, and supporting, a vertically arranged gear 60. The gear 60 meshes with a gear 61 supported within an opening 62 formed within the housing 58. The gear 61 is splined upon a drive shaft 63 having its bearings, in the lower set within the bars 18 and 19, and in the upper set within the bars 15 and 16. The gear 60 is rigidly attached to a vertical shaft 64 carrying a conventional type of chuck 65. The chuck 65 is adapted to receive and hold a conventional type of drill 66. The housing 58 is slidably carried upon guide rods 67 and 67', secured at their ends within the bars 18 and 19, and 15 and 16, respectively. Each drill housing, together with its associated elements, may be independently adjusted along the guide rods 67, whereby the several drills may be suitably arranged for drilling volumes of varying widths. It might be stated at this point that the upper and lower drills should be adjusted in vertical alignment. Means are employed for imparting rotation to the shafts 63, such means comprising upper and lower sprockets 68 and 69, which are in turn engaged by a sprocket chain 70. The lower shaft 63 carries, in addition to the sprocket 69, a second sprocket 71. The sprocket 71 is rigidly attached to the shaft 63 and is rotated through the medium of a sprocket chain 72. The sprocket chain 72, in turn, engages a small sprocket 73 carried upon the shaft of a motor 74. This motor 74 is suitably supported upon the base of the machine, as indicated at 75. A suitable shield 74' may be employed to protect the motor from drillings, incident to the drilling of the volumes. It is, therefore, obvious that

rotation of the motor 74 will impart rotation to the shafts 63, through the medium of the sprocket chain 72, sprocket wheel 71 and sprocket wheels 68 and 69, through the medium of the sprocket chain 70. The several sprocket wheels may be covered by a housing 76 secured to the frame of the machine in any convenient manner.

As clearly shown in Figs. 5 and 7, the normal position of the work table is such as to cause the plates 28 and 41 to overlie and underlie the drills 66. It therefore becomes necessary in order to drill a volume to move the table, and associated elements, rearwardly to a position whereby the drills 66 will be in alignment with the notches 29 and 42. When in the rearward position the table may be elevated, or lowered, upon the guide rods 12 and 14, to enable the operator 20 to drill the volume from above and below. When the table is in the forward, or normal, position, the pins 32 lie within the slots 31, thus preventing movement of the table in a vertical direction, as before stated. The 25 means to shift the table rearwardly comprise a pair of links 77 arranged below the table 22 and pivotally secured to the bearing brackets 27. The links 77 normally lie in a forward past-center position, and are pivotally connected, at their engaging ends, by a rod 78, the upper end of which is formed cylindrical and operates within slots 79 formed in the links 77. The rod 78 is carried by a suitable support 80, in turn pivotally mounted, as at 81, to a transversely extending rod 82 carried by the base frame 10. Thus it will be seen that a rearward swinging movement of the member 80 will result in the movement of the links 77, also rearward. As illustrated, the links 77 are connected with the underside of the table by means of a pin and slot arrangement 83. Thus, movement of the links rearwardly, or to their straight line position, will result in 40 the shifting of the table rearwardly, by reason of the sliding of the guide rods 26 through the brackets 27. Rearward movement is limited by the abutment of the bar 24 against the brackets 27, in which position 45 the plates are properly positioned over the drills 66.

Means are provided to raise and lower the table and associated elements, after the table has been shifted rearwardly to disengage the pins 32 from the slots 31. This elevating and lowering means comprises a pair of rack bars 84 arranged outwardly of, and rigidly attached to, the bearing brackets 27, and arranged in parallelism with the guide rods 12 and 14. The rack bars 84 have engagement with gears 85, rigidly attached to a transverse shaft 86 having bearing in the bars 18 and 19. The means for rotating the shaft 86 comprise a worm wheel 87 and a worm 88. The worm wheel 87 is rigidly at-

tached to the shaft 86 and is arranged outwardly of the gear 85. The worm 88 is mounted upon a longitudinally extending shaft 89, and is adapted to mesh with the worm wheel 87. The shaft 89 is suitably supported in bearing blocks 90, carried by the bar 19. The shaft 89 extends forwardly of the machine, and carries a hand crank 91. It will, therefore, be obvious that rotation of the hand crank 91 will result in rotation of the worm 88, worm wheel 87, shaft 86 and, consequently, the gears 85. Thus the rack bars 84 will be elevated, or lowered, depending upon the rotation of the parts, and consequently the table and associated elements. Idler rollers 92 are suitably pivoted to the bars 18 and 19, adjacent the rear edges of the rack bars 84, whereby such rack bars will be positively held in engagement with the gears 85 at all times.

To facilitate the raising and lowering of the table 22, means are provided whereby the table and its associated elements are counter balanced. This counter balancing means comprises a supporting bar 93, adapted to 90 partake of vertical movement upon fixed guide rods 94, carried by the base frame 10. The supporting bar 93 is connected to the upper ends of the rack bars 94 through the medium of flexible members, such as a chain or cable 95, passing over pulleys 96, suitably pivoted upon the rear ends of the bars 15 and 16. The supporting bar 93 is adapted to receive a plurality of counter balancing weights 97, through the medium of which 95 the table and the work carried thereon may be conveniently balanced.

The member 80 is swung rearwardly by an operating handle 98, rigidly attached thereto, and means are employed for locking the table in the forward, or inoperative, position, through the medium of the links 77, rod 78, member 80, and operating handle 98. This locking means comprises a pivoted latch 99 adapted to engage a stationary, co-acting, latch 100 carried by a rod 101, extending transversely of the base frame 10. The latch 99 is pivoted to the operating handle 98, as shown at 102, and carries an extension 103 adapted to be engaged by the 105 finger of the operator. The numeral 104 designates a conventional type of electric switch for operating the motor 74. It is unnecessary to describe the switch in detail, with the exception that it comprises an operating lever 105, arranged outwardly of the casing proper, and adapted to have pivotal engagement with a link 106, in turn pivotally carried upon the operating handle 98, as shown at 107. When the operating handle 110 is in the latched position, the table 22, and associated elements, have been moved to forward, or inoperative, position, and the switch 104 has been moved to the "off" position, through the medium of the link 106 115 120 125 130

and lever 105. Thus it will be seen that when the table is moved to the forward position, the drills are automatically stopped.

During the operation of the machine, it often becomes necessary to adjust the drills to accommodate volumes of varying sizes. It therefore becomes necessary to provide means for locking these drills in position after they have become set. To take care of this requirement the drill housings 58 are provided, upon their upper faces, with pins 108, adapted to be engaged by longitudinally extending, perforated, lock bars 109 and 110. The upper locking bar 109 has its ends 10 bent rearwardly at a right angle, as clearly shown at 109', and has pivotal connection, as at 111, with suitable brackets 112, carried by the bars 15 and 16. This pivotal connection enables the bar 109 to be swung 20 upwardly for disengagement with the pins 108 carried by the upper drill housings 58. By this means the operator is permitted to adjust the housings longitudinally of their supporting bars 67. The lower locking bar 110 has its end bent rearwardly at a right angle, as at 110', and is pivotally attached to the end bars 20 and 21, as shown at 113, whereby such bar 110 may be swung in a vertical plane, similar to the bar 109, to permit of the adjustment of the lower drill housings 58 longitudinally of their supporting bars 67. When it is necessary to adjust either the upper or lower drills it is desirable that the machine shall become inoperative, and to accomplish this, the locking bar 109 is connected with the latch 34, through the medium of a link 114, pivoted to the latch 34 by means of a pin 115. The locking bar 110 is connected with the latch 40 34 through the medium of a link 116, also engaging about the pin 115. Either the upper or lower bars, 109 and 110, may be moved independently of the other bar, but, in either case, it is desirable that the latch 45 34 shall be swung upwardly upon its pivot 111 to the locking position, as illustrated in Fig. 17. The links 114 and 116 have a lost motion connection with the latch 34, as shown, through the medium of slots 114' and 116', whereby either link may move upwardly, to operate the latch 34, without disturbing the position of the corresponding bar. Thus it will be seen that when either the locking bar 109 or 110 is lifted out of 50 engagement with the pins 108, the latch 34 will have moved upwardly, as in Fig. 17, and engages about the pin 32, to prevent rearward movement of the table 22 during such time as the bar is elevated. Thus injury to an operator because of rotating drills is avoided, by reason of the fact that all 55 parts become inoperative when the table is in forward position. As a further safeguard against injury to the operator it is desirable that adjustment of the drills shall

be prevented while the machine is in operation. To accomplish this the latch 37 has been provided as before described. Thus when the table has been moved rearwardly the pins 32 have moved outwardly of the 70 bars 20 and 21, and the latch 37 has swung to the vertical position, by gravity, and lies in the path of movement of the finger 36. Thus, elevation of the bars 109 and 110 will be prevented because of their engagement 75 with the latch 34, through the medium of the links 114 and 116. It will therefore be seen that the operator is safeguarded against injury by the rotating drills in either position of the machine. 80

As stated, the bars 109 and 110 are provided with a plurality of perforations adapted to engage over the pins 108 carried by the drill housings. These perforations are 85 equidistantly spaced and correspond, in number and alignment, with the notches 29 and 42 of the plates 28 and 41, whereby the drills will be positively and correctly positioned for the passage of the drills through the notches 29 and 42, when the table is elevated or lowered. 90

Means are provided for accurately measuring and shaping the metallic backs to be applied to the volume. These backs comprise a metallic sheet preferably covered by canvas, or other material, cemented thereto. The material of these backs forms no part of the present invention, but as the backs are supplied to the jobber in standard sizes in sheet form, it becomes necessary that the 95 material shall be suitably measured and shaped to fit the particular volume under construction. 100

Bolted, or otherwise attached, to the bar 17 is a plate 117 extending longitudinally 105 of said bar for approximately its entire length, and parallel therewith. The plate 117 extends above the upper edge of the bar 17 and has its rear face beveled, as at 118. Bolted, or otherwise secured, to the upper 110 face of the bar 17 is a second bar 119, the upper face of which is flush with the upper edge of the plate 117. The bar 119 is spaced from the plate 117 and has its forward face beveled, as at 120, corresponding to the beveled face 118. An outer plate 121 is rigidly held in spaced relation to the plate 117, and is of approximately the same size thereof. This plate has its outer upper edge beveled, as at 122, corresponding to the beveled face 118. The plate 121 is held in spaced relation to the plate 117 by spacing washers 123, and the plate is held in position by bolts 124. Mounted between the plates 117 and 121, is a 115 gauge plate 125, slightly longer than the plates 117 and 121, and adapted to partake of vertical, reciprocatory, movement between these plates. The plate 125 is provided with a plurality of vertically arranged slots 126 for permitting the movement of the plate 120 130

about the spacing washers 123. Ribs 127 are formed upon the rear face of the gauge plate 125, to relieve friction and facilitate the sliding movement of this plate. The plate 125 carries stop elements 128 at its opposite ends, for engagement against the lower face of overhanging portions 129 of blocks 130. The blocks 130 are rigidly bolted to the bar 17, as at 131. The overhanging portions 129 carry pivot pins 132, in turn receiving eyes 133, carried by a bending bar 134. The bar 134 is arranged in parallel relation with the bar 17, and its outer face is approximately flush with the outer face of the plate 117. This bar 134 is adapted to swing forwardly and downwardly upon the pivots 132, as clearly shown in Fig. 10. Arms 135 are carried by the upper face of the bar 134 to facilitate the swinging of this bar. Means are provided for raising and lowering the plate 125, in accordance with the thickness of the volume under construction. This means comprises arcuate cam members 136, pivotally attached to the rods 11 and 13 by means of fixed brackets 137. These members carry rearwardly extending operating arms 138 adapted to be engaged by lugs 139, carried by a plate 140, in turn carried by the pressure bar 38. Springs 141 are attached to the arms 138 and to the bar 17, as at 142. These springs normally tend to urge the arms 138 upwardly against the lugs 139, and thus movement of the bar 39, up or down, will result in the swinging of the arms 138 upon their pivots 137 to cause the cams 136 to rotate against the lower edge of the plate 125, to raise or lower such plate. Thus the elevation of the plate 125 is determined by the elevation of the pressure bar 38. The plates 140, carrying the lugs 139, are normally urged outwardly by means of springs 143 surrounding rods 144 carried between the bars 39, and having pivotal connection with bolts 145, carried by the angular extension of the plate 140, and operating through a slot formed in the outer plate 39. Thus it will be seen that the plates 140, carrying the lugs 139, may be moved inwardly against the tension of the springs 143 when it becomes necessary for the arms 138 to engage against the upper lugs 139. It will be noted I have provided an upper and a lower set of these lugs 139. The lower set operates under normal conditions, and the upper set under abnormal conditions, as will be hereinafter more fully set out. The purpose of these upper lugs is to enable an operator to accurately measure, and cut off or turn under, surplus material of the metallic back, when it becomes necessary to employ large sheets in the binding of very small volumes. As clearly shown, the lugs 139 are beveled whereby, when the pressure bar is again elevated, they will permit the passage of the arms 138 to a position beneath the lower lugs 139.

The operation of the device is as follows: The material to be bound, including suitable hinged covers, is placed upon the table 22, beneath the pressure bar 38, with its longitudinal edges against the evener board 49. The small portion of the cover adjacent its hinge is equal in width to the binding edges of the back. The table 52 is then swung upwardly to the position where it rests against the edges of the plates 28 and 41, and the material is then moved forwardly until its edges lie evenly thereagainst. The hand wheel 47 is then rotated in a direction to cause the pressure bar 38 to move downwardly upon the material to be bound, thus clamping it firmly in position upon the plate 28. If necessary the drills may now be adjusted longitudinally of the bar 67 to bring two, or more drills beneath, and above, the volume at points desired for drilling. The volume is now in position and the next operation is the forming of the back therefor.

The pressure bar having been moved to clamping position against the volume, has moved the arms 138 a predetermined distance, and has caused the cams 136 to rotate against the lower edge of the plate 125, thus moving this plate to a predetermined position of adjustment for taking up the excess material of the backs. A sheet of material is then placed in the space between the plates 117 and 121, and rests upon the upper edge of the plate 125. In this position, the depths to which the material extends correspond to one-half of the excess material to be taken up, in accordance with the thickness of the particular volume under construction. The bar 134 is then swung downwardly as illustrated in Fig. 10, bending the material over the beveled face 122, as clearly shown. To complete this bending, the bar 134 is raised and the material removed and again placed against the beveled face 122. The bar 134 is brought down a second time, which completes the initial bending. The material is then reversed and the other side bent back upon itself, each bending representing a half of the excess material and the two bendings taking up all the excess material. It now becomes necessary to bend the edges of the back material to a right angular position, as illustrated in Fig. 12. The degree of this bending is the same in all volumes. The bent portion illustrated at 146 is then inserted in the space between the beveled faces 118 and 120, so that its edge rests upon the top of the bar 17, and the bar 134 is then swung upwardly to the position illustrated in Fig. 11. It is to be understood that these bending operations take

place upon both edges of the back material. The back is now formed as shown in Fig. 12, and is then placed with its bent portions over the forward edges of the plates 28 and 41, so that it overlies the notches 29 and 42. The volume is now ready to be drilled.

The operator grasps the handle 98, with one finger lifts the latch 103, and raises the lever 98 to cause the table to move rearwardly. This movement in turn operates the switch 104 for starting the motor and imparting rotation to the drills. The operator next rotates the handle 91 for elevating and lowering the table. The table is lowered first upon the drills of the lower set and then elevated for engagement with the drills of the upper set. The drilling operation is now complete, and the operator again grasps the handle 98, swinging it downwardly for moving the table forwardly, and incidentally stopping the rotation of the drills. Interlocking binding nails, similar to those illustrated in Fig. 14, are now inserted in the drilled holes, from above and below the bound volume.

It now becomes necessary to release the volume so that the nails may be firmly set in place. In order to do this it is first necessary to raise the pressure bar sufficiently to enable the operator to remove the volume. Inasmuch as the back extends over the edges of the plates 28 and 41, movement of the pressure bar upwardly would ordinarily disarrange the volume. It is to avoid this that the plate 28 has been hinged at its rear edge. Thus when the pressure bar is raised slightly to release the volume, the back is raised also, carrying with it the lower plate 28. It is then only necessary for the operator to pull the volume forwardly until its bound edge rests upon the table 52. A few blows from a hammer will firmly set the locking nails in place.

As before stated, it often becomes necessary to bind unusually thin volumes, and in the absence of the proper size back material, the operator is obliged to employ back material much too large, and it is then a matter of overlapping the excess material, or cutting it down to the proper dimensions. To determine the proper amount of material to trim off, the operator moves the plates 140 inwardly against the tension of their springs, allowing the arms 138 to be drawn upward by the springs 141, so that such arms will bear against the upper lugs 139. The pressure plate is then lowered to clamp the material upon the table. The back material is then inserted between the plates 117 and 121 as before, and the depth to which the material enters between the plates indicates the amount of excess material to be removed from the back. The measuring and forming of the back is then identical as

before. As the pressure bar is again elevated, the arms 138 will pass over the lugs 139 automatically to their normal position.

It is to be understood that the form of the invention herewith shown and described is to be taken as the preferred one, but it should be understood that various changes in the shape, size and arrangement of parts may be resorted to without departing from the spirit of the invention or the scope of the subjoined claims.

Having thus described my invention, what I claim and desire to secure by Letters Patent of the United States is:

1. In a book binding machine, the combination with a work table of means for clamping leaves of a volume thereon, drill mechanism for piercing the leaves of the volume, means for advancing and retracting said table so the leaves are under or retracted from under the drills, locking mechanism for preventing the operation of the drills when the table is in retracted position and permitting the drills to operate when the table is in advanced position.

2. In a book-binding machine, the combination with a work table, of means for clamping the leaves of a volume thereon, means for advancing and retracting the work table, means for raising and lowering said work table, and drill mechanisms above and below said work table into engagement with which the leaves of the volume are brought when the table is raised and lowered after having been advanced in a position between the drill mechanisms.

3. In a book-binding machine, the combination with a work table and a clamping mechanism carried thereby, of means for raising and lowering said work table, means for advancing and retracting said work table for properly positioning matter to be bound, for drilling, horizontally disposed drill actuating shafts disposed above and below the level of the work table, a motor, means for driving from said motor to both of said shafts, a plurality of drills adjustable along each of said shafts and driven therefrom throughout all positions of adjustment, a locking element for locking the drills in adjusted position, and elements connected to and controlled by said locking element for preventing operation of said drills whenever said locking element is out of locking position.

4. In a book-binding machine, the combination with a work table mounted for forward and rearward movement, of a drill mechanism associated therewith, said table when in the forward position adapted to properly position matter held thereon for drilling, a motor for driving the drill mechanism, a switch for controlling the motor, and a common operating handle for actuat-

ing said switch and shifting said table so that the motor can only be started when the table is in its forward position.

5. A machine of the character described, comprising a table mounted for both horizontal and vertical movement, a drill mechanism associated therewith comprising a plurality of adjustable drills, a locking mechanism for preventing movement of said 10 drills to effect an adjustment thereof, and means for preventing movement of the said locking mechanism when the table is in its rearmost position.

6. In a machine of the character described, 15 the combination with a table provided with locking extensions, of a member upon each side of the table having a recess into which said extensions enter when the table is in forward position, latches adapted to engage 20 the said extensions, a drill mechanism comprising a plurality of longitudinally adjustable drills, a locking bar for holding said drills in adjusted position, and a connection between said locking bar and said latch.

25 7. In a machine of the character described, the combination with a table provided with locking extensions, of a member upon each side of the table having a recess into which said extensions enter when the table is in forward position, latches adapted to engage 30 the said extensions, a drill mechanism comprising a plurality of longitudinally adjustable drills, a locking bar for holding said

drills in adjusted position, a connection between said locking bar and said latch, and 35 co-acting latch members held out of operative position by said extensions when the table is in forward position, and movable, when said extensions are withdrawn by the rearward movement of the table, into alignment 40 with said latches to prevent operation of the same.

8. In a machine of the character described, the combination with a table mounted for forward and rearward movement and for 45 vertical movement, of a clamping means associated with said table, drill mechanisms above and below the level of said table, the drill mechanisms comprising a horizontally extending bar having a plurality of drill 50 housings longitudinally adjustable therewith, locking bars for locking said drill housings in adjusted positions, a connecting rod extending between said locking bars, a latch lever having lost motion connection 55 with said connecting rod and comprising a hooked extremity, an extension upon the table with which said hooked extremity is adapted to engage, and a co-operating latch member held out of position by the extremity 60 of the table when the table is in forward position and movable into alignment with the latch to prevent operation of the latter when said table is moved rearwardly.

ALEXANDER B. ROE.
